CLAIM

The ornamental design for an in-circuit tester console,
as shown.

DESCRIPTION

FIG. 1 is a front elevational view of the in-circuit tester console showing our new design, the rear elevational view not shown being substantially plain and unornamented;

FIG. 2 is a right side elevational view;

FIG. 3 is a bottom plan view;

FIG. 4 is a left side elevational view;

FIG. 5 is a top plan view; and

FIG. 6 is a top, front, and left side perspective view thereof.

FIG. 2

FIG. 4

FIG. 1

FIG. 3
